UNITED STATES PATENT OFFICE.

DELOS P. HEATH, OF PEORIA, ILLINOIS.

PRESSURE-CONTROL SWITCH.

Application filed July 22, 1926. Serial No. 124,190.

This invention relates to an automatic pressure control switch construction particularly adapted for use with mechanical refrigerating machines such as are used in refrigerators wherein an electric motor is cut in or out so as to operate the refrigerating machine at the times when it is desired and stop it at other times. The pressure control system is to be preferred over a thermostatic control as it is of more sturdy and durable construction and can be quickly and accurately adjusted and is not subject to such variations as is the temperature system so that the period of operation of the refrigerating machine is more accurately and better controlled.

It is an object and purpose of the present invention to construct a switch unit which may be conveniently used together with a fuse block and fuses in a single control box and wherein a longitudinally expansible and contractible bellows is utilized, being expanded on increase of pressure and contracted on lowering thereof, such expansion beyond a predetermined amount acting automatically through a switch to start the motor in operation and the contraction when the pressure has reached the desired stage snapping the switch so as to break the circuit in which the motor is disposed and stop the machine from further operation until the pressure has again raised to the maximum amount on the low pressure side of the system to which the invention is applied. A further object and purpose of the invention is to provide this switch with springs acting against the pressure of the longitudinally contractible and expansible element or bellows, as it is commonly known, which are easily capable of adjustment for obtaining a different range when desired. A still further object of the invention is to construct a control box which while it completely encloses and covers the bellows, such bellows may be very easily removed and replaced at any time if it should be necessary without disturbing the box other than to remove the cover over the bellows. Many other objects and purposes than those stated, particularly the construction of the apparatus in a practical and economical manner using sheet metal parts to a large extent, will appear as under-

standing of the invention is had from the following description taken in connection with the accompanying drawings, in which

Fig. 1 is an elevation of the control box looking at the open side thereof and disclosing the switch mechanism and fuse block and fuses located within said control box.

Fig. 2 is a fragmentary longitudinal vertical section through one end of the control box and the switch mechanism located therein.

Fig. 3 is a fragmentary vertical section through the switch structure per se.

Fig. 4 is a horizontal section through such switch structure on the plane of line 4—4 of Fig. 1.

Fig. 5 is a perspective view of a somewhat modified form of structure of the switch wherein the mercury tube switch is replaced by a simple knife switch.

Fig. 6 is a view similar to that shown in Fig. 1 but showing only the switch structure at one end of the control box, said switch structure being of a somewhat different form.

Fig. 7 is a transverse vertical section through the control box at the right of the switch mechanism shown in Fig. 6 and looking toward the left to show said switch mechanism in elevation.

Fig. 8 is a perspective view of the bellows cover plate, and

Fig. 9 is a fragmentary transverse vertical section on the line 9—9 of Fig. 6.

Like reference characters refer to like parts in the different figures of the drawings.

The control box which is of any suitable metal, preferably aluminum, has a vertical back 1, vertical ends 2 and 3, a bottom side 4 and a top side 5, all cast integrally. A lug or ear 6 projects upwardly from the bottom 4 between which and the back 1 a lever 8 substantially of channel form is pivotally mounted at its lower end on the pivot 7. From the flanges or sides of the lever 8 substantially rectangular enlargements 9 extend to one side of the same having openings 10 therethrough, as shown in Fig. 1. A rod 11 extends through and is rotatably mounted on the back 1, at its outer side being equipped with a handle 11^a turned at right angles while the inner end portion of the rod extends

through the openings 10 and a block 12 is fixed to the rod also extending through said openings. The block is connected at one end to the rod 11 and extends therefrom so that 5 on turning the rod the block acts as a cam against either side of the openings 10. The rod 11 may be turned to three positions in one of which the lever 8 is free to move a limited distance either way on the pivot 7, in another 10 of which the lever is held at extreme left position, and in the third position it is held at extreme right position, as is evident.

A horizontal rod 13 passes through the end 2 of the control box and then through the upper end of the lever 8. A coiled spring 14 is located around the free end portion of the rod between said lever and the adjusting and locating nuts 15 threaded onto the end of the rod. The outer end of the rod is equipped 20 with a knurled head 13^a by means of which it may be turned. The outer end portion is likewise threaded where it passes through the end 2 of the control box and carries a locating nut 16 which bears against the outer side of the end 2, as shown. The spring 14, it is evident, may be adjusted so as to be compressed to a greater or less degree by the nuts 15 and the lever 14, the tendency thereof being to move the lever to the left, as shown in 25 Figs. 1 and 2. Adjustment may also be made by means of the nut 16 and head 13^a.

Between the sides of the lever 8 a distance below the rod 13 a cross bar 17 is integrally cast therewith hooked over which is one end 30 of a coiled tension spring 18. This spring is disposed horizontally and extends toward the end 2 of the control box, at its outer end surrounding and being permanently attached to a nut 19. A threaded rod 20 passes through 35 a slot 21 in the end 2 of the box and thence is threaded through the nut 19. At its outer end the rod is equipped with a head 22 so that rod 20 may be adjusted inwardly or outwardly through the nut 19 and control the tension 40 of spring 18 and the force of the pull that it exerts on the lever 8.

At the lower corners of the box between the end 2 and the lower portion of the lever 8 a corrugated metal bellows 23 subject to longitudinal contraction or expansion, is located, both ends of which are closed, the end nearest the lever 8 being equipped with a point 45 which fits a suitable recess in the side of the lever 8 a short distance above the pivot 7. The opposite end of the bellows seats against a boss projecting inwardly from the end 2 of the control box through which a short length 50 of pipe 25 extends, the outer end of which is connected with a flexible metal tube 26 through which the pressure at the lower side 55 of the system is carried to the interior of the bellows. The pipe 25 is threaded at its outer and inner ends to receive the nuts 27 and 28, there being a suitable gasket interposed between the boss mentioned and the end of the 60

bellows and another between the inner side of the end of the bellows and said nut 28 so as to make an air or gas tight connection. The back 1 of the control box is cut away around the bellows leaving an opening 29, 70 best shown in Fig. 9, and a slot 25^a is cut inwardly through the boss mentioned and the adjacent part of the end 2 of the control box so that the bellows with the attached parts 25 and 26 may be readily installed or may be 75 as readily removed and replaced without disturbing the control box in any other way even though it is permanently secured in place in connection with the refrigerating machine with which it is to work. This opening is normally covered by a cover 30 arc shaped in cross section and having ends, one of which is equipped with two spaced apart fingers 31 adapted to pass one above and the other below the pipe 25 and be clamped against the 80 end of the control box when the nut 27 is tightened.

A post 32 is cast integrally and extends horizontally from the back 1 of the control box. At its end a U-shaped member of sheet 90 metal is rigidly secured comprising two vertical spaced apart legs 33 connected by a bottom 34. A second U-shaped member of sheet metal is located at the upper end of the first of said members and is inverted having 95 two spaced apart sides 35 connected by a top 36. The sides 35 pass within the sides 33 of the first U-shaped member and each is formed with an outwardly extending lug 37 which seats in a notch or recess in the adjacent side 100 33 of the lower member. A coiled spring 38 under tension is disposed between and connected at its ends respectively to the bottom 34 and the top 36 of the two members, as best shown in Fig. 3.

The two sheet metal U-shaped members described and mounted in the manner described form a toggle and the spring which is disposed between them serves to snap the upper movable member from one side to the 110 other as the line of force of the spring passes from one side to the other of the dead center line of the toggle.

Above the toggle member described, a third U-shaped member of sheet metal is located 115 having two spaced apart sides 39 connected by a bottom 40. This member is mounted on a rod 41 which is attached to and projects horizontally from the back 1 of the control box. A sleeve 42 is located around the rod 120 and properly positions the third U-shaped member directly over the toggle. To the under side or bottom 40 of this member a member also formed of sheet metal is soldered or otherwise permanently secured having a 125 top side 44 which lies against the under side of the bottom 40 and is secured thereto from one edge of which a web 45 extends downwardly, it at its vertical edges being formed with flanges 46 which extend one to each side 130

of the upper movable member of the toggle 50 whereby when this upper movable member of the toggle is shifted from one side to the other the construction pivotally mounted on the rod 40 is turned about said rod from right to left and vice versa.

Between sides 39 a glass tube 43 is clamped at one end of which are two spaced apart contact heads 47 connected respectively to

10 the ends of two rods 48 and 48^a which in turn are connected to the wires 49 of the electric circuit in which the motor for operating the refrigerating machine is placed. Within the tube 43 a quantity of mercury indicated at

15 50 is placed, and with the tilting of the tube from one side to the other the mercury freely flows from one end of the tube to the other.

When it is in the position shown in Fig. 1 it is evident that the circuit is broken inasmuch as there is no electric connection between contacts 47 but when the tube is tilted to the opposite side, as shown in Fig. 3, both of the heads 47 are partly immersed in the mercury and the circuit is closed.

25 On one of the sides 35 of the upper movable member of the toggle a vertical channel 51 is secured (see Fig. 4). An arm 52 cast integral with the lever 8 has an end portion 53 turned at right angles so as to pass between

30 the flanges of the channel 51. It is evident that when pressure in the bellows 23 increases to a degree sufficient to move the lever 8 against the force of springs 14 and 18, said lever will be moved to the right drawing the

35 arm 52 with it and causing the upper member of the toggle to be turned about the axis of the pivot lugs 37 until such time as the force of the spring 38 passes across the dead center line of the toggle whereupon the tube 43 is

40 snapped quickly from the position shown in Fig. 3 to that shown in Fig. 1 with a resultant break of the electric circuit and stopping of the motor. Conversely when the pressure in

45 the bellows 23 reduces permitting the force of springs 14 and 18 to move the lever to the left with the contraction of the bellows 23 when the line of force of spring 38 crosses

50 the dead center line of the toggle, the switch will be snapped in the opposite direction, the circuit completed and the motor started in operation.

While I have shown the mercury tube type of switch in Figs. 1, 2 and 3 it is obvious that other types of switches may be used and in

55 Fig. 5 an equivalent switch for opening and closing the circuit is disclosed. In such construction the tube 43 and its connections and the U-shaped member supporting the same are eliminated and from the web 45 of the

60 member engaging with the upper movable member of the toggle a finger 54 is extended vertically, the same being adapted in one position to pass between the sides of a contact, such as that indicated at 55, and in an-

other position being entirely disengaged therefrom. This is a simple type of knife switch and is one which can be substituted for the mercury tube switch very readily, the circuit wires being connected one with the contact 55 and the other in any suitable manner, 70 electrically connected with the plates 54. The same effect in so far as stopping and starting the motor will be produced as with the mercury tube switch first described.

In Figs. 6 and 7 a somewhat different or 75 modified form of construction of the apparatus is shown. Instead of using the toggle construction such as shown in Fig. 3, at the end of the post 32 two spaced apart horizontal bars 56 are rigidly connected and held in 80 spaced apart relation from each other, these serving as a support for the pivotal mounting of a switch carrying member which is in the form of a casting having an upper horizontal side 57 from which two spaced apart 85 legs 58 and 59 depend between the bars 56 and are pivotally connected thereto. The upper or top side 57 is extended to one side and then turned vertically as indicated at 60 while at its opposite side the top 57 is provided with a horizontal bar 61 through which 90 two screws 62 pass the same being adjustable to different positions and lying directly over the upper edge of one of the bars 56.

The vertical part 60 serves as a support 95 for a U-shaped clamping member having sides 63 between which the glass tube 43 of the same character as that shown in Figs. 1 and 3 though with contacts at the opposite end, is clamped and secured. From the side 100 of the lever 8 an elongated projection 64 extends to which one end of a coiled spring 65 is secured, the opposite end being attached to the under side of the top 57 of the switch carrying member.

105 This construction serves the same purposes as that shown in Figs. 1, 2 and 3. As the lever 8 moves farther from the position shown in Fig. 6, to the right, with the increase of pressure in the bellows 23 the lower end of 110 the spring 65 moves with it and the line of force of the spring passes from one side to the other of the pivots by which the switch carrying member is connected to the supporting bars 56 causing the switch to snap and turn from the position shown in Fig. 6 to a position where it will be tilted in the opposite direction. The contact of the lower ends of the screws 62 with the upper edge of the bar 56 directly below, limits the extent of tilting 115 movement of the tube 43.

The construction of the class described is automatic in its action, is durable and efficient and not liable to get out of order, is easily adjusted to change the range, and the bellows 120 element which is the only part of the mechanism which may possibly fail, can be very readily removed for repair or replacement by a new element of the same kind. The spring 14 which may be termed the "range" 130

spring is used for regulation of the range of pressure between stopping and starting pressures. It usually is adjusted to a fixed position when it leaves the factory, which position does not thereafter need to be changed. The spring 18 which may be termed the "temperature" by its tension determines the pressure at which the switch will tilt to off position, it at all times being in direct opposition to the force of the bellows 23 against the lever 8. The pressure in the bellows must be sufficient to overcome the force of both of the springs before the lever will be moved far enough to tilt the tube to a position where the circuit is completed. The maximum range between stopping and starting pressures is attained when the spring 14 is adjusted to maintain tension against the lever 8 until said lever is almost in position necessary to tilt the tube 43 from its "on" to its "off" position. The minimum range is attained when the spring 14 does not exert pressure against the lever 8. An adjustment of the nut 22, so as to increase the tension in spring 18, will apply more force to the lever 8 in which case a higher temperature in the refrigerator may be had. As said before the spring 14 is seldom adjusted. However, should it be desirable to start the unit at a higher pressure operation of the control it can be very readily adjusted. The farther the spring 14 is moved away from the lever 8 the lower will be the pressure at which the motor starts.

35. By reason of the manual control of the lever 8 through the crank handle 11^a and the rod 11 of which it is a part, it is readily possible to hold the switch in either its off or its on position irrespective of what may be the condition of pressure in the refrigerating machine. At the neutral or intermediate point the apparatus is permitted to act automatically. There are many times when it is desirable to prevent the motor from running irrespective of pressure and also other times when it is desired to have it continuously running, and by reason of the manual control described either of these conditions may be very easily had.

50. This construction has been tested and tried extensively and has proved its practicability in such tests. The invention is defined in the appended claims and is to be considered comprehensive of all forms of structure coming within their scope.

I claim:

1. In a construction of the class described, a housing support having a base, a vertical side and a vertical end, said side at its lower portion near one end having an opening therethrough, an arm pivotally mounted at its lower end on said base, spring means acting on the arm to turn it in one direction, a corrugated metal bellows located in said housing opposite said opening in the vertical

side thereof and having one end bearing against the lower portion of the arm and the opposite end secured to the adjacent vertical end of the housing whereby said bellows may be readily replaced or removed through said opening, and a cover detachably connected to the housing over said opening.

2. A construction containing the elements in combination defined in claim 1, said arm at one side having a member extending laterally therefrom through which an opening is made, a shaft rotatably mounted on and passing through the vertical side of the housing, and means on the inner end of the shaft located in the opening in said member whereby, when said shaft is turned, said member may be fixed against movement at either of the two extremes of its movement, said member when occupying an intermediate position leaving the arm free to be acted upon by the bellows and said spring means.

3. In a construction of the class described, a housing support having a base, a vertical end, and a vertical side, said vertical side at its lower portion adjacent the end having an opening therethrough and said vertical end having a horizontal slot formed therein inwardly for a distance from the edge of said opening, an arm pivotally mounted on said support a short distance above the base and extending vertically, spring means tending to move the arm at its upper end toward the vertical end of the support, a corrugated metal bellows located between the lower end portion of the arm and said end of the support having one end bearing against the arm, a tubular member entering and connected to the opposite end of said bellows seated in said slot, a cover for the opening detachably connected to and on the outer side of the vertical side of the support, and a switch for making and breaking an electric circuit operatively connected with the arm to be moved thereby, substantially as described.

4. In combination, a housing support having a base, a vertical side and a vertical end, an arm pivotally mounted at its lower end on said support a short distance above the base, a rod passing through said end of the housing and through the upper end of the arm, said rod being threaded at its inner end, nuts threaded on the inner end of the rod, a compression spring on said rod between the arm and the nuts, means for adjusting the rod longitudinally through the said end of the support, a second spring connected at one end to the arm a distance below the upper end thereof, a nut secured at the opposite end of the spring, a rod passing through the end of the support and threaded through said nut, means on the outer end of the rod for turning the same, a movable switch operatively connected with the arm to move from circuit making to circuit breaking position or vice versa with the movements of the arm,

- a corrugated metal bellows subject to inner variations of pressure connected at one end to the end of the housing and at its opposite end bearing against said arm a short distance above its pivot, and means manually operable from outside of the housing for locking the lever against movement at either extreme of its movements whereby the switch will be held either in circuit making or breaking position irrespective of the condition of pressure in said bellows. 10
